UNITED STATES PATENT OFFICE.

OSWALD S. PULLIAM, OF PITTSBURG, PENNSYLVANIA.

CAR-TRUCK BOLSTER.

No. 821,812.

Specification of Letters Patent.

Patented May 22, 1906.

Application filed October 6, 1905, Serial No. 281,647.

To all whom it may concern:

Be it known that I, OSWALD S. PULLIAM, a citizen of the United States, residing at Pittsburgh, in the county of Allegheny and State of Pennsylvania, have invented new and useful Improvements in Car - Truck Bolsters, of which the following is a specification.

The object of my invention is to provide a new and improved car-truck bolster particularly designed to take care of all torsional strains to which truck-bolsters are subjected in practice.

A further object of the present invention is the production of a truck-bolster of such form that it may be built up of a plurality of T-pieces suitably joined or cast as an integral structure.

To these ends my invention consists, of a car-truck bolster, in the novel features of construction and in the combination of parts, all as fully hereinafter described and claimed.

In the accompanying drawings, which illustrate applications of my invention, Figure 1 is a top plan view of a bolster constructed in accordance with my invention; Fig. 2, a side elevational view; Fig. 3, a cross-sectional view taken on line II II of Fig. 2, and Fig. 4 a cross-sectional view showing the bolster formed as an integral structure.

Referring to the drawings, the truck-bolster as illustrated in the form of Fig. 1 comprises the top or compression member, the bottom or tension member, and the vertical web joining said compression and tension members.

In this form of bolster the compression member is constructed of two T-pieces 2, each provided with a downwardly - projecting flange 3. In addition to the flange 3 each piece 2 has an edge flange, which flange extends above and below the top or compression member. The tension member and the web are formed of a single T-piece 4. The three T-pieces 2, 2, and 4 are joined together directly under the compression member by means of rivets 5, which latter are passed through the flange 3 of each T-piece 2 and through the upper edge of the web portion of T-pieces 4.

In the form of Fig. 4 the bolster is cast as an integral structure. The center-bearing 6 and the usual end bearings 7 are shown and may be secured to the compression member in any suitable manner.

What I claim is—

1. A car-truck bolster comprising a compression member, a tension member and a web connecting said members constructed of three T-shaped pieces, and means for securing the T-pieces together. 55

2. A car-truck bolster substantially T- shaped in cross-section, comprising a compression member having edge flanges extending above and below said member throughout the length of the member, a tension member, and a web connecting the compression 60 and tension members. 65

3. A car-truck bolster having a top member formed of two substantially T-shaped pieces, a bottom member and a web connecting the two members. 70

4. A car-truck bolster having a top member formed of two substantially T-shaped pieces, each provided with an engaging flange, a bottom member, and a web connecting the 75 said members.

5. A car-truck bolster having a top member formed of two substantially T-shaped pieces, each provided with an engaging flange, means for securing the flanges together, a bottom member, and a web connecting said 80 members. 85

6. A car-truck bolster having a top member formed of two substantially T-shaped pieces, each provided with an engaging flange, a bottom member, a web connecting said 85 members, said web located between the two engaging flanges, and means for uniting the flanges and web. 90

7. A car-truck bolster having a top member formed of two substantially T-shaped pieces, a bottom member and web formed of a single substantially T-shaped piece, and means for securing the web to the top member. 95

8. A car-truck bolster having a top member formed of two substantially T-shaped pieces, each provided with an engaging flange, a bottom member and web formed of a single substantially T-shaped piece, said web located between the flanges and means for uniting the web and flanges. 100

In testimony whereof I affix my signature in presence of two subscribing witnesses.

OSWALD S. PULLIAM.
